TETHERED BALL TOY

Richard L. Collver, 226 20th St. E.,
Saskatoon, Saskatchewan, Canada

Filed Nov. 2, 1970, Ser. No. 25,764

Claims priority, application Canada Oct. 28, 1970

Term of patent 3½ years

Int. Cl. D21—01

U.S. Cl. D34—15

FIG. 1 is a perspective view of a tethered ball toy showing my new design;

FIG. 2 is a side elevational view with the ball omitted for convenience of illustration;

FIG. 3 is a reduced side elevation of the side opposite FIG. 2;

FIG. 4 is a front elevational view taken from the left of FIG. 2; and

FIG. 5 is a rear elevational view taken from the right of FIG. 2.

I claim:

The ornamental design for a tethered ball toy, as shown and described.
